UNITED STATES PATENT OFFICE

HENRY C. PRESTON, OF BALTIMORE COUNTY, MARYLAND, ASSIGNOR TO THE BLACK & DECKER MANUFACTURING COMPANY, OF TOWSON, MARYLAND, A CORPORATION OF MARYLAND

VALVE SEAT REAMER SLEEVE

Application filed June 16, 1931. Serial No. 544,808.

In the resurfacing of valve seats, the customary practice is to use a hand reamer to remove the hard surface which forms on the seat during the operation of the motor and to further cut away the main part of the metal, removal of which is necessary to the formation of the new seat before applying the stone or other means for lapping and finally smoothing the valve seat surface. These cutters or reamers in accordance with the present practice are mounted on a sleeve which is in turn mounted on an arbor or pilot which is held rigidly in the valve stem guide or bushing. In this way it is attempted to keep the cut of the reamer which, in effect, forms the new valve seat, in alignment with the valve stem guide with the object of centering the new seat or new seating surface and aligning it with the valve stem guide.

It has been found that a certain amount of wear takes place as to the inner surface of the sleeve and the outer surface of the arbor or pilot as the sleeve is rotated upon it in operating the cutter. In fact, a satisfactory result cannot be obtained under existing conditions without the exercise of unusual skill and diligence owing to the difficulty in so controlling the reamer cut as to cause the seating surface which is finally produced to be exactly centered, and aligned with the valve stem guide. This is largely due to the wear of the contacting surfaces of the sleeve and arbor or pilot.

To overcome these difficulties and produce a valve seat reaming apparatus whereby the new seating surface can be properly and exactly centered without variation and without the exercise of greater skill and diligence than that which is to be expected of the average mechanic engaged in the repair of motor vehicles and the like, is the object of the invention. To this end the invention provides an adjustable sleeve or hub for supporting the reamer on the pilot whereby any and all wear of the contacting surfaces of the reamer sleeve and pilot which may occur can be taken up, causing the reamer to be properly centered with the pilot at all times. The adjustable sleeve is also claimed in combination with a pilot which may include centering means at

the top and bottom of the guide to take up wear.

In the accompanying drawing I have illustrated a valve seat reamer with means for mounting the same on the pilot or arbor and means for centering the pilot, in accordance with my invention in the preferred form.

In the drawing:

Figure 1 is a section including the axis of a valve guide showing the arbor, the sleeve and the reamer assembled and in operative relation thereto, in accordance with the invention.

Figure 2 is an elevation of the reamer sleeve or hub.

Figure 3 is a top plan view of the same.

Figure 4 is a section on the line 4, 4 in Figure 1.

Referring to the drawing by numerals, each of which is used to indicate the same or similar parts in the different figures, the valve seat reaming apparatus as shown comprises an arbor or pilot 1, adapted to fit in the valve guide or bushing 2 and a valve seat reamer 3 with a sleeve or hub 4 carrying the reamer and mounted to rotate on the pilot or arbor 1.

In accordance with the preferred form of the invention, the sleeve or hub 4, which has a central bore or opening 5, to receive the arbor 1, is slotted or split preferably in a radial plane or substantially in line with a radius at 6, the split which may be in the form of a saw cut, extending from the outer surface inwardly to the central bore 5. In the form shown the cut or split 6 terminates short of the lower end at 8 and the lower portion of the sleeve is shown as tapered at 7 to provide a seat for the reamer. In the form shown the cut or split also extends a short distance into the wall of the sleeve at 9 on the opposite side of the bore from the cut 6. This gives additional flexibility to the sleeve, increasing the efficiency of the adjustment being described.

Immediately above the tapered portion 7, the sleeve 4 is shown as threaded at 10 and on this thread is seated a nut 11 preferably hexagonal, which is used to back the reamer off of the sleeve when it is desired to change

the reamer for a different size or for any purpose, it being understood that to seat the reamer in operative relation to the sleeve, it is forced on to the taper to cooperate with 5 which it has a correspondingly tapered opening indicated at 12 in Figure 1.

Above the threaded portion 10, the sleeve is formed with a projecting shoulder or collar 14, which may be integral with the 10 sleeve. The shoulder is shown as hexagonal or square as to its horizontal cross section so that it is conveniently engaged by means of any suitable wrench to rotate the reamer in the cutting operation. This collar is shown 15 as bored at 15 at right angles to the cut or split 6, crossing the same outside of the circular arbor opening 5, and in this hole 15 which is threaded for this purpose is seated a clamping screw 16 for adjusting the size 20 of the sleeve opening 5 to a neat running fit on the pilot as hereinafter described by closing the split 6 as desired.

The form of the arbor or pilot is also of interest. At a point spaced downwardly 25 from the upper end by a distance which may be equal to or a little greater than the length of the reamer sleeve 4 is a downwardly tapered frustro conical shoulder 17 of relatively gradual taper and the lower end portion of 30 the arbor is tapered downwardly from the diameter of the central portion at 18 which fits loosely within the valve guide 2 to a relatively small screw threaded lower end at 19, the taper being indicated by reference character 20. The tapered shoulder 17 and the taper 20 are preferably so spaced that in the operative position of the parts they come at 35 the upper and lower ends, respectively, of the valve guide or bushing 2. Cooperating with the lower end of the pilot 1 is a split threaded centering tip 21. This tip is formed externally of a diameter normally somewhat less than the valve guide or bushing with which the apparatus is to be used. 40 The tip is provided with an enlarged tubular portion 22 extending upwardly and having an opening at 24 corresponding to the taper at 20 and adapted to admit the tapered portion to be expanded thereby. This portion 22 is split radially and longitudinally 45 at 23 to provide for expansion of the portion 22 in contact with the taper 20 on the pilot. Below this portion 22 is a relatively reduced threaded opening 25 in alignment with the 50 axis of opening 24 and adapted to receive and engage the threaded end 19 of the pilot or arbor 1. In operation the arbor 1 is passed downwardly through the valve guide until 55 the frustro conical collar or shoulder 17 engages the top end of the valve guide at 26 as shown, centering the upper end of the pilot or arbor. The lower end of the pilot which protrudes from the valve guide is engaged by the centering tip 21 which is 60 screwed up on the threaded end 19 by turn-

ing the pilot by means of a pin inserted through opening 28 at the top, forcing the taper 20 on the pilot into the opening 24 in the tip until the expansion of the tip and the spreading of the split 23 due to contact 70 of the tubular extension 24 with the taper 20 causes the outside of the tubular portion 22 to contact and engage closely with the walls of the valve stem guide. In this way 75 the pilot or arbor is definitely centered and rigidly clamped in the valve stem guide.

A suitable reamer or cutter 3 having been pressed on to the taper 7 of the sleeve 4, the sleeve carrying the reamer or cutter is passed over the top end of the pilot so that it comes 80 in contact with the valve seat to be repaired or reamed at 27. Then the screw 15 is tightened closing the cut 6 until the sleeve has a neat fit on the pilot and can be rotated without any suggestion of side play. This adjustment of the sleeve 4 to the pilot disposes 85 of any tendency on the part of the reamer to cut off center due to wear of the contacting surfaces of the sleeve and pilot. The pilot being rigidly supported in and duly central 90 with the valve guide in the manner described, or in any suitable manner as by use of any type of pilot which fits closely in the valve guide, the reamer cut is positively centered in relation to the valve guide without regard to 95 wear of the various parts and without the exercise of unusual skill on the part of the operator.

I have thus described specifically and in detail a device for centering a valve seat 100 reamer, pilot and sleeve, embodying the features of my invention in the preferred form, the description being specific and in detail in order that the manner of applying the invention and constructing and operating and using 105 the same may be fully understood, however, the specific terms therein are used descriptively rather than in a limiting sense, the scope of the invention being defined in the claim. 110

What I claim as new and desire to secure by Letters Patent is:

A valve seat reamer sleeve adapted to carry a reamer, the same being tapered at its lower end to form an arbor for the reamer, the central aperture of the sleeve being adapted to engage a valve seat surfacing pilot, the sleeve immediately above the taper being threaded and provided with a nut for backing the reamer off the seat, the sleeve being slotted in the direction of the axis for substantially its entire length downwardly to a point approaching the lower end of the taper, the slot extending upwardly to and through the upper end of the sleeve, the sleeve being provided 115 immediately above the backing off thread with an angular slotted collar for engagement with a handle or wrench, said collar being bored in a direction which is substantially tangential to the pilot, and threaded 120

125

130

to receive a screw which engages the sleeve on both sides of the slot and a screw in said bore for adjusting the diameter of the sleeve to the pilot.

5 Signed by me at Towson, Baltimore County, Maryland, this 9th day of June, 1931.

HENRY C. PRESTON.
